UNITED STATES PATENT OFFICE.

KATHERINE C. KANE, OF OLDTOWN, MAINE.

DUST-PAN.

1,107,961.

Specification of Letters Patent. Patented Aug. 18, 1914.

Application filed June 14, 1913. Serial No. 773,670.

To all whom it may concern:

Be it known that I, KATHERINE C. KANE, a citizen of the United States, residing at Oldtown, in the county of Penobscot and State of Maine, have invented new and useful Improvements in Dust-Pans, of which the following is a specification.

This invention relates to dust pans and has for its object to so construct a pan of this character that the dirt and material when swept upon the pan will gravitate into the refuse space at the forward end thereof and thus be prevented from being spilled.

A further object of the invention is to so construct a pan of this character whereby the same will firmly stand in upright position on the floor when in use.

A still further object of the invention is the provision of a pan of this character which is simple in construction, strong, durable and efficient for the purpose for which it is intended.

In the drawing forming a portion of this specification and in which like numerals of reference indicate similar parts in the several views:—Figure 1 is a perspective view of the device constructed in accordance with my invention. Fig. 2 is a vertical transverse sectional view of the device. Fig. 3 is a back side view of the device. Fig. 4 is a bottom plan view of the device. Fig. 5 is a view showing the device in a dumping position. Fig. 6 is a sectional view taken on line 5—5 of Fig. 4. Fig. 7 is a sectional view taken on line 6—6 of Fig. 4.

Referring to the drawing by numerals the device comprises a bottom 1 which is secured in any suitable manner to the end walls 2 and 3, and a handle 4 which projects upwardly from the end wall 2. The bottom has a front, flat horizontal portion which terminates to provide a guard plate 5 which diverges from the forward edge of said bottom rearwardly a short distance above the horizontal portion of the bottom and defines therewith a refuse space or pocket 6. The remaining portion of the bottom is curved upwardly and rearwardly a considerable distance above the adjacent edge of the guard plate 5 so that the dirt and material when swept into the pan will strike against the curved portion of said bottom and gravitate into the refuse space or pocket 6 and thus prevent it from being spilled.

The end walls 2 and 3 are of substantially triangular formation so as to retain the for-

ward edge of the pan in close contacting engagement with the floor, and the straight edges of said end walls are arranged to rest upon the floor whereby the pan will firmly stand in upright position when in use. The lower straight edges of the end walls are bent inwardly for a portion of their length equal to the length of the said horizontal portion of the bottom to provide attaching flanges 7 which are arranged upon the bottom and secured thereto in any suitable manner. The upper inclined edges of the said end walls are formed to provide outwardly extending reinforcing flanges 8 to which is also secured in any suitable manner the side edges of the guard plate 5. The end walls 2 and 3 together with the flanges 7 extend a slight distance beyond the rear edge of the bottom so that the pan may be tilted rearwardly and supported by said end walls and flanges at the proper inclination whereby the dirt and material may be directed by the curvature of the bottom into any suitable receptacle.

What I claim, is:—

1. As an improved article of manufacture, a dust pan comprising side walls, a bottom arranged between the sides and having its upper edge formed to provide an inclined guard plate, and having a front horizontal flat portion defining a pocket by the intervening space therebetween and said guard plate, said bottom being curved from a point approximately midway of its length to provide an upwardly curved portion terminating below the upper edges of the sides and adapted to direct the material into said pocket when swept on the pan.

2. As an improved article of manufacture, a dust pan including triangular shaped sides having their lower edges bent for the major portion of their length to provide inwardly disposed attaching flanges, a bottom having a front flat horizontal portion secured to said attaching flanges and a rear portion curved from a point adjacent the rear end of said flanges and terminating below the upper edge of said sides, and a guard plate extended rearwardly from the forward edge of said bottom and terminating below the upper edge thereof.

3. As an improved article of manufacture, a dust pan comprising side walls of triangular formation having their upper edges formed to provide outwardly disposed flanges, a bottom having a front horizontal

flat portion extended to provide an upwardly curved rear portion terminating below the upper edges of said sides, and said flanges being extended at an angle rearwardly of the said sides whereby the latter and said angularly disposed portions of the flanges support the pan inverted at a proper inclination so that the curved portion of the

bottom serves to direct the material into a suitable receptacle when discharged.

In testimony whereof I affix my signature in presence of two witnesses.

KATHERINE C. KANE.
